UNITED STATES PATENT OFFICE.

WILLIAM B. OLIVER, OF COLLINGSWOOD, NEW JERSEY.

FLYING-MACHINE

1,096,263.

Specification of Letters Patent. Patented May 12, 1914.

Application filed November 12, 1909. Serial No. 527,602.

To all whom it may concern:

Be it known that I, WILLIAM B. OLIVER, a citizen of the United States, and a resident of Collingswood, in the county of Camden and State of New Jersey, have invented certain new and useful Improvements in Flying-Machines, whereof the following is a specification, reference being had to the accompanying drawings.

10 In said drawings the invention is illustrated as applied to an aero-plane, but as will be stated hereafter, its scope is not restricted to such embodiment.

One of the great difficulties in aviation is 15 the tendency of the aeroplane to tilt, either laterally or in a fore-and-aft direction, owing, for instance, to varying air pressures upon differing parts, or to the change of position of the aviator. While manually 20 operable devices are provided to correct this tendency, such devices require great skill and constant attention on the part of the aviator for their operation, such demands upon him, being of course, additional to 25 those which are required for the steering of the aeroplane upon a given course.

For convenience of description, the term "normal equilibrium", may be employed to indicate the desired relation between the 30 main axes, fore-and-aft and transverse, of the aero-plane, or other flying machine, and the plane of the horizon, although it will be noted that such relation is not necessarily one of parallelism at all times, since in the 35 act of rising or descending, the fore-and-aft main axis of the structure must be inclined to the horizon, and in describing a curved flight, inclination of the transverse main axis is desirable.

40 The object of my invention is to automatically maintain the normal equilibrium of a flying machine in a predetermined position, or series of positions, during flight, thus relieving the aviator from the necessity of 45 constantly manipulating the regulating devices, and even permitting him to shift his position upon the structure itself. Said automatic control may be employed in combination with the usual devices for manually 50 controlling the regulating devices.

In the accompanying drawings, Figure I, represents in perspective and diagrammatically, a biplane, without the rear extension usually employed in connection therewith, 55 and shows typical elements which are related to the purposes of the present invention.

tion. Fig. II is a front view illustrating the automatic control for the air valve 37; Fig. III is a partial side elevation thereof; Fig. IV is a vertical transverse section through 60 the valve chest 32; Fig. V is a detail view of the pressure cylinder controlling the movement of the front planes 6 and 7.

As the general structure of the device is well known, it is not deemed necessary to 65 describe in detail the various parts thereof, except in so far as they possess functions which directly relate to the present invention.

In Fig. I, 1, and 2, indicate the movable 70 side planes, or wings, whose adjustment affects the lateral position of the aeroplane during flight, said wings being hinged to the framework at 3, and 4, respectively. 6, and 7, indicate the pair of front planes by means 75 of which the fore-and-aft position of the aeroplane is affected, said planes 6, and 7, being secured to a rectangular frame 5, which is attached to the axle 8, rotatably mounted in the forwardly projecting extension bars 9, of the main framework. The side wings 1, and 2, are controllable in opposition to one another, by means of cords 10, 11, 75, and 76, which pass around suitable guiding pulleys, the cords 75, and 76, 80 being joined together by a movable piston rod 77, extending through the cylinder 72, which will be described later on. Manual control of said wings is obtained by attaching the cords 10, and 11, to the vertical arm 90 12, mounted upon the end of a rock shaft 13, which is provided with suitable bearings in the framework; and can be turned to the right or left, by means of the hand lever 14. The front planes 6, and 7, are controllable 95 in unison, their movement being effected by means of a lever arm 17, secured to the axle 8, and pivotally attached to the front end of a connecting rod 18, which is pivotally attached at 46, to a piston rod 43, which is 100 provided with a handle 19, whereby the aviator can push or pull the connecting rod and tilt the frame 5, which supports said front wings 6, and 7. The hand lever 14, and the handle 19, are so located as to be 105 accessible from the seat 20, which is intended to be occupied by the aviator. The mode of manipulating these several planes or wings, and the principles of their operation are, of course, well understood, so that it is 110 not necessary to here make any extended reference thereto.

The feature of the present invention resides in an organization which is intended to automatically control the side planes 1, and 2, and the front planes 6, and 7, independently of any manual operation, and as a direct consequence of the departure of the aero-plane from a predetermined normal equilibrium, either laterally or fore-and-aft. To this end I provide a power operated system, whereby the side planes 1, and 2, or the front planes 6, and 7, or both sets thereof, may be mechanically shifted, and I combine, with said system, controlling elements actuated by gravity, in accordance with changes of position of the respective main axes of the aero-plane, with relation to the plane of the horizon. In the instance shown, the power operated system is pneumatic, the source of supply being an air-pump 25, located in convenient relation to and driven by the internal combustion engine 27, which runs the propeller. Said air pump discharges into a reservoir 28, having an outlet pipe 29, which leads to a forwardly extending pipe 30, communicating by means of a branch pipe 31, with a valve chest 32, containing a rotatable valve, whose details are shown in Fig. IV, which represents a vertical transverse section through the valve chest on a plane passing through the axes of the inlet and outlet pipes connected therewith. Referring to said Fig. IV, it will be noticed that the valve chest 32, has an inlet port 33, into which the branch pipe 31, leads, and that it also has lateral discharge ports 34, and 35, which are in diametrical alignment with one another, and an exhaust port 36, which, together with inlet port 33, are in quadrant relation to the discharge ports. The valve 37, is mounted upon the rotatable stem 39, and has the configuration shown, that is to say,—when it is in what may be termed the neutral position, indicated by the sectional view of Fig. IV, the actuating fluid is cut off from both the discharge ports 34, and 35, and from the exhaust port 36. Rotative movement however, in either direction will result in throwing the inlet port 33, into communication with one of the discharge ports 34, and 35, the other one of said ports being simultaneously thrown into communication with the exhaust port 36.

Disregarding for the moment, the elements by which the valve is to be rotated, I will now trace by reference to Fig. I, the connections from the discharge ports 34, and 35, respectively. The port 34, communicates by means of a pipe 40, with one end of a pressure cylinder 41, while the other discharge port 35, communicates by means of the pipe 42, with the other end of said cylinder. The cylinder 41, is provided with a piston mounted upon the piston rod 43, sliding in suitable guides in the framework, the front end of said rod being pivotally se-

cured at 46, to the rod 18, which shifts the front planes 6, and 7. The rod 43, protrudes through the cylinder, at each end, and is provided with a spiral compression spring 44, at each extremity, only one of these springs being visible in Fig. I. Said springs cushion the movement of the piston to some extent, and also tend to restore the piston to a central position in the cylinder. The cylinder 41, is also provided with bleeder cocks 45, as shown in the enlarged view of Fig. V, which can be thrown fully open by means of the rod 48, a spring 49, tending to restore said cocks to a slightly open position, the extent of the orifice thus permanently open being determined by the adjustable stop collar 47. Said bleeding orifices modify the immediate effect of the admission of compressed air, and also can be thrown fully open by the aviator to permit the manual shifting of the piston rod 43, by means of the hand lever 19, without undue effort. To avoid confusion, these bleeder cocks and their adjunctive mechanism are omitted from the general view of Fig. I. It will thus be seen that by the admission of air under pressure to either end of the cylinder 41, a corresponding movement of the piston rod will be effected and the front planes 6, and 7, will be tilted upward or downward.

Automatic control of the valve 37, to admit the air in the desired direction, is effected by the elements shown in front view in Fig. II, and in partial side elevation in Fig. III. The valve stem 39, protrudes through the valve chest as shown in Figs. II, and III, and carries at its outer extremity a handle 50, rigidly attached thereto by means of a set screw 51, passing through the collar 52, the axis of the handle being in line with median axial plane of the valve. A plate 53, preferably disk-shaped as shown, is freely mounted upon the valve stem 39, in rear of the collar, said plate having a plurality of ratchet teeth, indicated comprehensively at 54, upon a segment of its upper periphery, which teeth may appropriately correspond with degrees of the circumference of a circle, and may be numbered accordingly, on either side of a zero point, which is visible through an aperture 55, in the handle 50. A pendulum rod 56, is rigidly attached to the ratchet-disk and carries at its lower end a weight 57, which is preferably of disk form but has sufficient mass to be capable of shifting the valve 37, under the action of gravity. Said pendulum weight 57, is provided with a pair of guide sectors 58, which limit its movement to one of rotation upon the axis of the stem 39, and thus prevent the strain which might otherwise occur through tilting in directions transverse to the desired plane of movement.

Upon the rear of the handle 50, is mounted a spring-actuated grip-lever 60, whose lower end 61, is adapted to engage with the ratchet teeth 54. By means of this grip-lever and ratchet disk the handle 50, (and consequently the valve stem 39), may be locked to the pendulum rod 56, in any desired angular relation, throughout the range of the ratchet teeth 54. In the position in which the parts are represented in Figs. II and III, the grip lever is engaged with the ratchet teeth at zero, the axis of the handle 50, and consequently the median plane of the valve 37, being in direct alinement with the axis of the pendulum rod 56, and hence, when the alinement of the ports 34, and 35, of the valve chest is horizontal, the pendulum rod 56, will be vertical, and the valve 37, will be in the neutral position shown in Fig. IV. If now the valve chest be tilted laterally in either direction, the pendulum rod 56, will maintain its position with relation to the center of gravity of the earth, and since the said pendulum rod is locked to the valve 37, the valve chest will shift its position with relation to said valve, so as to open communication between the inlet port 33, and one of the discharge ports 34, or 35, according to the direction of the inclination, the other of said ports being thrown into communication with the exhaust port 36. If, however, the handle 50, be turned and the grip lever be brought into engagement with the ratchet teeth upon either side of zero, the median plane of the valve 37, will have been turned with relation to the axis of the pendulum rod 56. Since the pendulum rod remains constantly vertical, a horizontal relation of the ports 34, and 35, will correspond with an open position of the valve, in one direction or the other, and the valve will only be closed when the ports 34, and 35, assume an angular relation to the plane of the horizon, corresponding with the arc of departure from zero, represented by the point of engagement of the grip lever 60.

Returning now to the general view of the aero-plane in Fig. I, it will be noted that the valve chest 32, is mounted in parallel relation to the fore-and-aft main axis of the aero-plane, and that the pendulum rod 56, is free to swing in a fore-and-aft direction. When the aero-plane tilts in that direction, a movement of the valve chest 32, with relation to the pendulum rod, will take place, such movement resulting in changes of position of the valve ports with relation to the valve 37. Thus, assuming the grip lever 60, to be set at zero, the neutral position of the valve will correspond with a horizontal position of the fore-and-aft main axis of the aero-plane, since the alinement of the discharge ports 34, and 35, is horizontal. So long as this position is maintained, there

will be no tendency on the part of the pendulum to move with relation to the valve chest, and consequently the valve 37, will remain in a closed position, as shown in Fig. IV. If, however, the front end of the aero-plane tilts downward, the pendulum will maintain its vertical position and a rotary movement of the valve chest 32, with relation to the valve 37, will occur in such direction as to open communication between the inlet port 33, and the discharge port 35. The compressed air passing through this channel to the pipe 42, is delivered to the front end of the cylinder 41, forcing the piston and piston rod 43, rearward and pulling the connecting rod 18. The point of attachment of the connecting rod 18, to the lever arm 17, being above the axle 8, this rearward pull of the rod 18, will shift the frame 5, carrying the planes 6, and 7, so as to raise their front ends and depress their rear ends, thus affording a deflection of their surfaces adapted to produce a rise of the front end of the aero-plane. As soon as this rising movement has progressed sufficiently to again bring the main fore-and-aft axis of the aero-plane to a horizontal position, the ports 34, and 35, of the valve chest will resume their horizontal position with relation of the valve, so that access of compressed air to the cylinder 41, will be cut off. Thereupon, the rear spring 44, will tend to shift the piston to its central position, the bleeding orifices permitting the escape and access of air on opposite sides thereof, and this movement of the piston rod will occasion a forward thrust upon the connecting rod 18, which will tend to restore the normal position of the frame 5, and planes 6, and 7. If, on the other hand, as the result of this action, or from any other cause, the front end of the aero-plane rises beyond the predetermined position of normal equilibrium, fore-and-aft, the reverse relative movement of the valve chest with relation to the pendulum rod will occur, and compressed air will be admitted to the rear end of the cylinder 41, forcing the piston forward and thrusting upon the piston rod 43, and connecting rod 18, so as to tilt the frame 5, and deflect the forward ends of the front planes 6, and 7, downwardly. This position of the front planes is adapted to cause a descent of the front end of the structure. Hence, the tendency of the pendulum, when the valve stem is adjusted at zero, will be to maintain the main fore-and-aft axis of the structure horizontal. If, however, the aviator desires to set the apparatus so that the normal tendency shall be, for instance, for the front end of the aero-plane to rise, the handle 50, and grip lever 60, are shifted toward the rear of the structure (which is toward the left in Fig. II), the catch being set in that one of the notches which corre-

sponds to the desired angle of flight with relation to the plane of the horizon. By reason of this adjustment the pendulum rod 56, will be at an angle to the median plane of the valve 37, so that when the alinement of the discharge ports 34, and 35, is horizontal, (the pendulum rod remaining vertical), communication will be established between the inlet port 33, and the discharge port 35. 5

Access of air to the front of the cylinder will thereupon be permitted, and the rearward movement of the piston will result in tilting the front planes 6, and 7, so as to direct the flight upward. When, however, 10 the flight has attained an angle corresponding to the setting of the valve with relation to the pendulum rod, the relative position of the valve ports and valve will be such as to close the discharge port 35, and hence there will be no further tendency to tilt the plane 15 until downward departure from that direction of flight occurs, when the effect of the pendulum will be to reestablish communication between the ports 34, and 35, and thus give the proper corrective movement to the 20 front planes 6, and 7. As the control of the valve by means of the pendulum is constant and immediate upon any departure from the normal equilibrium, fore-and-aft, the necessary 25 adjustments of the planes 6, and 7, will occur promptly, but too great a degree of sensitiveness is prevented by reason of the springs 44, and also by the bleeding apertures in the cylinder 41, which afford a primary 30 relief against the full pressure at the commencement of each movement, and permit the escape and access of air on either side of the piston, when the valve is assuming a closed position. The side wings 1, and 2, are controlled by a similar group of 35 elements arranged at right angles to those just described. In the drawings (Fig. I) the details of the valve chest and pendulum are not visible, since they are supposed to be concealed by the front portion of the apparatus, but it will be understood that in this case the axis of the valve stem lies in a fore-and-aft direction, or at right angles to the axis of the stem 39, and hence the pendulum is free to swing laterally instead of fore-and-aft. 40

Assuming the existence of a valve, valve chest, pendulum and connecting elements identical with those just described, but 45 working at right angles thereto, the pipes 70, and 71, lead from the respective discharge ports of the valve chest and cross one another, as shown, to opposite extremities of the cylinder 72, which is arranged transversely to the aero-plane. This cylinder is 50 provided with a piston and a piston-rod 77, which protrudes at each end, the protruding ends being provided with springs 73, and 74, respectively, whose functions are similar to 55 those of the springs 44. Cords 75, and 76,

lead from the respective ends of the piston rod, to points of attachment on the rear edges of the side planes 1, and 2, so that when one of said cords is pulled the rear portion of the plane to which it is attached, 70 will be raised, and the motion transmitted through the cords 10, and 11, will cause the rear portion of the opposite plane to be depressed. Assuming now that the valve which controls access of compressed air to 75 the cylinder 72, is set at zero, the position of normal equilibrium laterally, will be when the main transverse axis of the aero-plane is horizontal, and consequently the alinement of the discharge ports of that 80 valve chest is also horizontal. In this position the valve will close said ports, the piston in the cylinder 72, will be in its neutral position, and the planes 1, and 2, will be horizontal. If, however, the aero-plane tilts 85 laterally, the displacement of the valve chest with relation to the pendulum rod will cause the valve to open communication between the inlet port, and that one of the discharge ports which is tilted below the horizontal 90 line. Thereupon, compressed air will be admitted to the cylinder 72, at the extremity which is toward the high side of the structure. The air will cause the piston rod 73, to pull upon the cord attached to 95 the rear edge of the side plane upon that side of the structure which is highest, thus raising that side plane and (by means of the cords 10, and 11), depressing the rear edge of the side plane upon 100 that side which is lowest. The tendency of the side planes in their new position, will be to restore the main transverse axis of the aero-plane to a horizontal position, whereupon, the supply of compressed air 105 being shut off from the cylinder, the springs 73, and 74, will tend to bring the piston to the central position, access and escape of air being permitted by the bleeders of the cylinder. In this case, as in the one previously described, the pendulum rod can be adjusted at any desired angle to the median axial plane of the valve, so that the closed or neutral position of the valve shall correspond with a tilt of the transverse main axis of the structure at any predetermined angle to a horizontal plane.

The above described automatic controlling mechanism does not interfere with the use of the ordinary manual controlling 120 mechanism for effecting the desired movements of the front and side planes, since, by opening the bleeder cocks 45, of the respective cylinders to the full extent, the movement of the piston, which accompanies the exercise of manual control, will not be seriously impeded. Manual control of the bleeder cocks 45, is attained by shifting their rods 48, in one direction, and obviously if the cylinders are not so located as to per- 125

mit the rods to be conveniently reached by the aviator from his position upon the seat 20, cords (not shown in the drawings), may readily be connected therewith to facilitate 5 operation. The employment of the spring 49, renders it only necessary to positively shift the cocks 45, toward the full open position, since they will be automatically returned by the spring 49, to the normal 10 position of partial opening. By means of the adjustable stop 47, said cocks can be adjusted so as to afford any desired constant area of opening for the normal bleeding required.

15 Having thus described a particular embodiment of my invention, I desire it to be understood that neither the applicability thereof, nor my claims thereto, are limited to such embodiment. Thus, in any flying 20 machine, whether of the "heavier than air type", or of the balloon type, which is provided with suitable mechanism, adapted to determine the position of the fore-and-aft axis, or the lateral main axis of the structure, with relation to the general plane of 25 the horizon, automatic control of said mechanism may be accomplished by the same general principle of construction and mode of operation.

30 The essence of the invention resides in the following characteristics: First, that I employ power actuated operating mechanism for said determining members; second, that I employ controlling devices for the 35 power, which are characterized by the fact that an element thereof partakes of the tilting movements of the general structure with reference to the plane of the horizon, while a correlated element maintains what may 40 be considered as a fixed relation to the plane of the horizon, so far as concerns tilting of the general structure in a given direction; and third, that the movement of said first mentioned, or tilting, element of the controlling 45 mechanism, with relation to the second or comparatively fixed element, shall apply or shut off the power from the operating mechanism. Hence, it must be understood that the organization described in detail in 50 the foregoing specification, is simply typical of the application of my invention, and that the character of the flying machine, its directing devices, the power actuated operating mechanism and the controlling mechanism for the power, are each and all susceptible of variation without departure from 55 the spirit of my invention.

I apply the general term "equilibrium maintaining devices", to indicate comprehensively the deflecting elements, such as 60 wings, planes, etc., which affect the position of the main axis, or axes, of the general structure, with relation to the general plane of the horizon. I apply the term "co-tilt-

ing" to one element of the controlling device to indicate that said element partakes of the general tilting movement of a main axis of the structure, fore-and-aft, or transverse, or both. I apply the term "quasi-stable", to the correlative element of the 65 controlling device, to indicate that said element, under ordinary conditions, maintains a fixed relation to the general plane of the horizon as against movement of the structure in a particular direction, although, as is 70 obvious from the foregoing description, said stable element may partake of the general movement of the structure in other directions than the one for which this constancy of relative position is important. In the 75 instance shown, the quasi-stable element is a pendulum, but its function could obviously be performed by any equivalent device capable of maintaining a comparatively fixed position with relation to the other element 80 or elements. These terms I consider desirable because they avoid too great circumlocution in the language of my broad claims. For the same reason I employ the term "flying 85 machine" to indicate comprehensively 90 the various types of structures susceptible of control by a system embodying my invention.

I do not herein claim broadly in an airplane the combination of a main plane, lateral dip-correcting means comprising surfaces adjustable to different angles of incidence to the air flowing past the plane, longitudinal dip-controlling means, a gravity-influenced weight for operating the lateral dip-correcting means, and manually-operated devices independent of the weight for actuating the longitudinal dip-controlling means. Nor do I claim in an air ship, a horizontal plane, balancing wings at opposite sides of the planes adjacent to the transverse ends thereof, a vertically tilttable blade at the end of the machine for directing the vertical angle of flight, separate hinged depending and swinging members 95 having their axes disposed at substantially right angles to each other, connections between one of said swinging members and the wings for automatically controlling the lateral dip of the machine in either direction, 100 and other connections between the other swinging member and blade for controlling the angle of flight or inclination of the machine in the direction of travel. Furthermore, I do not claim in a flying machine 105 broadly a pressure cylinder, piston and piston rod, the latter being operatively connected to an equilibrium-maintaining device, with a fluid pressure supply for the cylinder, automatic controlling means for said 110 supply, and cushioned means, such as a spring connected with said piston rod and opposing the movement thereof under the 115 120 125

pressure of the fluid, whereby shock is avoided upon the application of the power to the equilibrium-maintaining device.

I claim:—

6. 1. In an automatic controlling system for a dirigible air-craft, said system comprising a valve chest, co-tilting with said air-craft, the combination, with said valve chest, of a valve and valve stem rotatable with relation 10 thereto; a pendulum freely mounted on said valve stem; a lever rigidly attached to said valve stem; and means for effecting engagement between said lever and said pendulum, whereby the valve may be rotatably adjusted 15 with relation to the axis of said pendulum and set in different positions.
2. In a dirigible air craft, the combination of an equilibrium-maintaining device; a pressure cylinder piston and piston rod, said 20 piston rod being operatively connected with said device, and being also manually movable independently of the power; a source of supply for fluid under pressure to said cylinder; an automatic controlling mechanism 25 for said fluid; and a bleeding device for said cylinder, whereby free manual operation of the equilibrium-maintaining device, through the medium of the piston rod, is permitted in the absence of application of power.
3. The combination of an elevating plane, 30 a fluid pressure cylinder operatively connected with the plane, a rotary valve for controlling the flow of fluid to the cylinder, a pendulum depending from the valve for rotating the same to effect automatic adjust- 35

ment of the plane, and means on the stem of the valve for rotating the valve independently of the pendulum to adjust the said plane.

4. The combination of an elevating plane, 40 a fluid-pressure cylinder operatively connected with said plane, a rotary valve for controlling the flow of fluid to the cylinder, a pendulum depending from the valve for rotating the same to effect automatic adjustment of the plane, a handle fixed to said valve, and means coöperating with said handle for indicating a predetermined adjustment 45 of the valve relative to said pendulum.

5. The combination of an elevating plane, 50 a fluid pressure cylinder operatively connected with said plane, a rotary valve for controlling the flow of fluid to the cylinder, a pendulum depending from the valve for rotating the same to effect automatic adjustment of the plane, a handle fixed to said valve, a disk loosely mounted on the valve adjacent said handle and provided at its edge with a series of indicating notches, and a grip-lever carried by said handle for engaging certain of said notches to indicate a predetermined adjustment of the valve relative 55 to the pendulum.

In testimony whereof, I have hereunto signed my name, at Philadelphia, Pennsylvania, this eleventh day of November, 1909.

WILLIAM B. OLIVER.
